UNITED STATES PATENT OFFICE.

CHARLES LINE, OF CHICAGO, ILLINOIS, ASSIGNOR TO MECHANICAL UTILITIES CORPORATION, OF CHICAGO, ILLINOIS, A CORPORATION OF ILLINOIS.

HEATER FOR CARBURETERS OR THE LIKE.

1,321,462.

Specification of Letters Patent.

Patented Nov. 11, 1919.

Application filed October 30, 1916. Serial No. 128,358.

To all whom it may concern:

Be it known that I, CHARLES LINE, a citizen of the United States, residing at Chicago, in the county of Cook and State of Illinois, have invented a certain new and useful Improvement in Heaters for Carbureters or the like, of which the following is a full, clear, concise, and exact description, reference being had to the accompanying 10 drawings, forming a part of this specification.

My invention relates to electric heaters and is particularly concerned with heaters of the type suitable for warming the liquid 15 fuel which is commonly employed in modern internal combustion engines, particularly automobile engines.

One of the particularly disadvantageous features of the internal combustion engine 20 has been the necessity for starting the same. This was cured in the automobile particularly, by the employment of electric starting apparatus. Under ordinary conditions the power stored in the electric storage battery 25 is sufficient and generally more than sufficient to turn the engine over until it begins to run under its own power.

However, under severe weather conditions 30 and especially where fuel oil of a lower vaporization point is employed, it is impossible to start the engine when the parts are cold.

The object of my invention is to provide a compact but powerful heater suitable for application to carbureters of substantially 35 all types with a minimum of expense and bother in attaching.

In the accompanying drawings which form a part of the present specification, I have illustrated one manner in which my invention may be carried out.

Figure 1 is a perspective view of a heater constructed according to my invention, showing the same in the process of assembling;

Fig. 2 is a cross section at one of the terminals, and

Fig. 3 is a diagrammatic illustration of the manner of applying the heater to a well-known type of carbureter.

The most convenient place to apply the 50 heat and the place where it will do the most good is at the float chamber of the carbureter since in this receptacle is contained the liquid fuel which is first drawn upon in starting the motor. It is not intended that 55 the heater that I have shown be employed

for heating all of the liquid, although I do not wish to limit the invention to heating the liquid only during the starting period. The entire heater 1 is made flexible so that the same may readily be wrapped around 60 the float chamber 2 of a carbureter 3 without completely inclosing the float chamber 2. The heater 1 comprises a thin outer metallic sheet 4 which is stamped with a number of fingers 5 extending from the edges 65 thereof, as shown in Fig. 1. Suitable terminals 6 and 7 are mounted on the sheet 4 and are connected respectively to one pole of the battery 8 and to the switch 9. The other terminal of the switch 9 is connected 70 to the opposite pole of the battery 8. As shown in Fig. 3, the fingers 5 are bent over the top of the float chamber 2 and serve to maintain the heater 1 in position. If it is desired to place the heater 1 at a lower position on the float chamber the same is accomplished by lacing a pair of wires 10 across the top of the float chamber. These wires are fastened in suitable holes formed in the lugs 5, as shown in Fig. 1. The shell 80 4 of the heater is provided at each end with a pair of lugs 12, 13, and the ends are drawn toward each other by means of wires passing through the ends of the lugs.

The heater is constructed as follows: The 85 outer shell 4 comprises a strip of thin sheet metal which is provided with the fingers 14 struck up from each edge of the metal, as shown in Fig. 1. Next to the shell 4 is placed a thick strip of asbestos 15, or other 90 suitable heat insulating and electrical insulating material. Upon the strip of asbestos 15 is placed the active heating element 16 which is preferably formed of a piece of suitable resistance wire of the proper dimensions and output to draw a fairly heavy current from the battery 8. I prefer to have this heater so constructed that it will draw from 4 to 10 amperes from the usual 6 volt battery which is employed for starting purposes. Over the resistance element 16 is placed a thin strip 17 of asbestos or other 100 similar electrical insulating material. A strip of thin sheet metal 18, preferably perforated, as shown, in order to make the same 105 as flexible as possible, is laid next to the insulating strip 17 and the fingers 14 are then bent over or clenched in order to hold the parts firmly together.

It is to be noted that if a solid flange in- 110

stead of the separate fingers 14 were employed the resulting structure would be too stiff to be wrapped around different sizes of float chambers.

5. The ends of the strip are bound together by a plurality of fingers 19, which are also bent over to hold the ends of the various strips and the shell. The ends of the resistance wire 16 are connected to the terminal 6 by means of a screw 20 passing through an insulated bushing 21 in a hole near the end of the shell 4. A suitable nut 22 holds the terminal 6 against the insulated bushing 21 but allows it to be placed in any 10 convenient position for the wires 23 and 24 which lead to the switch and to the battery.

A clip spring 25 is adapted to be snapped upon the heater 1 to hold the same in firm contact with the float chamber. Two 20 standing parallel beads 26 and 27 are punched in the outer shell 4 and these beads prevent the clip spring 25 from shifting upward or downward on the heater 1.

It can be seen from the above that I have 25 provided an inexpensive heater of simple construction which can be applied to any make of carburetor and apply the heat where it is needed.

I am familiar with a number of different 30 constructions wherein an electric heater is employed to heat the nozzle of a carburetor, or is suspended in the air passages of a carburetor, but my device is not to be confused with such constructions inasmuch as the 35 fuel passes by such heating means too rapidly to receive any degree of heat. According to my invention the heat is applied to a sufficient bulk of the material to enable the motor to start, but due to the fact 40 that the float occupies a considerable space in the interior of the chamber, I have an ideal condition for imparting heat to the gasolene in that it is in contact in a thin annular ring with a large metallic surface 45 upon the outside of which my heater is applied.

What I claim is:

1. In an electric heater, a heating element, 50 flexible insulating means upon each side of said heating element, a thin strip of flexible metal upon one side of said insulating strips, a thin strip of metal upon the outside of said insulating strips, said latter sheet having fingers struck up therefrom and extending 55 over and embracing the edges of said inner sheet of metal and terminals for said heating element, said terminals secured to said outer sheet of metal, said heater being

substantially flat upon its inner surface adapting it for close contact with the 60 face of the object to be heated.

2. In a heater of the class described, a flexible heating element, flexible sheet of insulation upon each side of said element, a sheet of flexible metal upon the inside of 65 said element, a flexible sheet of metal substantially coextensive with said inside sheet of metal upon the outside of said sheet of insulation, said outer sheet of metal having fingers struck up from the edges thereof, 70 said fingers being bent over the edges of said inner sheet and fingers or lugs struck up from the edge of said outer sheet for supporting said heater upon a carburetor 75 float chamber or the like.

3. In a heater of the class described, a pair of insulating strips, an electric heater between said strips, a thin sheet of metal substantially coextensive with said strips, a thin sheet of metal upon the outside of said 80 strips, said outer sheet of metal having fingers extending over the strips of insulation and over the edges of said inner sheet to hold the parts together, lugs struck up from the edges of said outer sheet and 85 cables for drawing said lugs together in order to cause the heater to grip the object to be heated and integral projections extending from said heater adapted to engage the object to be heated to prevent relative 90 lateral movement of the heater.

4. An electric heater for carburetors comprising a flexible metallic girth, means engaging the girth for drawing the latter into close engagement about the carburetor, an 95 electric heating coil in the girth, and means for supporting the girth, said means also engaging the carburetor to prevent the girth from slipping downwardly thereabout.

5. An electric heater for carburetors comprising a flexible metallic girth, means engaging the girth for drawing the latter into close engagement about the carburetor, an electric heating coil in the girth, and means for supporting the girth, said means comprising an inwardly extending lug arranged at substantially right angles to the upper edge of the girth for engagement with the shoulder of the carburetor, to support the girth from slipping downwardly thereabout.

In witness whereof I hereunto subscribe my name this 27th day of October A. D. 1916.

CHARLES LINE.
